(57) **CLAIM**

I claim the ornamental design for the collapsible over the sink colander, as shown and described.

DESCRIPTION

FIG. 1 is a top view of the collapsible over the sink colander; FIG. 2 is a front view of the collapsible over the sink colander;

FIG. 3 is a back view of the collapsible over the sink colander;

FIG. 4 is a bottom view of the collapsible over the sink colander;

FIG. 5 is a left side view of the collapsible over the sink colander;

FIG. 6 is a right side view of the collapsible over the sink colander;

FIG. 7 is a perspective view of the collapsible over the sink colander; and,

FIG. 8 is a perspective view of the collapsible over the sink colander, shown with the extension arm in a retracted position.

1 Claim, 4 Drawing Sheets
